The ornamental design for a light emitting diode, as shown and described.

DESCRIPTION

FIG. 1 is a front side view of a light emitting diode in accordance with a first embodiment of my new design;

FIG. 2 is a rear side view of the light emitting diode in accordance with the first embodiment of my new design;

FIG. 3 is a top plan view of the light emitting diode in accordance with the first embodiment of my new design;

FIG. 4 is a bottom plan view of the light emitting diode in accordance with the first embodiment of my new design;

FIG. 5 is a right side view of the light emitting diode in accordance with the first embodiment of my new design;

FIG. 6 is a left side view of the light emitting diode in accordance with the first embodiment of my new design;

FIG. 7 is a front perspective view of the light emitting diode in accordance with the first embodiment of my new design;

FIG. 8 is a rear perspective view of the light emitting diode in accordance with the first embodiment of my new design;

FIG. 9 is a front view of a light emitting diode in accordance with a second embodiment of my new design, the only difference between the second and the first embodiment being that the front surface is translucent in the second embodiment;

FIG. 10 is a front perspective view of the light emitting diode in accordance with the second embodiment of my new design;

FIG. 11 is a front side view of a light emitting diode in accordance with a third embodiment of my new design, the only difference between the third embodiment and the first embodiment being the shape of the attachment portion of the light emitting diode;

FIG. 12 is a rear side view of the light emitting diode in accordance with the third embodiment of my new design;

FIG. 13 is a top plan view of the light emitting diode in accordance with the third embodiment of my new design;

FIG. 14 is a bottom plan view of the light emitting diode in accordance with the third embodiment of my new design;

FIG. 15 is a right side view of the light emitting diode in accordance with the third embodiment of my new design;

FIG. 16 is a left side view of the light emitting diode in accordance with the third embodiment of my new design;

FIG. 17 is a front perspective view of the light emitting diode in accordance with the third embodiment of my new design;

FIG. 18 is a rear perspective view of the light emitting diode in accordance with the third embodiment of my new design;

FIG. 19 is a front view of a light emitting diode in accordance with a fourth embodiment of my new design, the only difference between the fourth and the third embodiment being that the front surface is translucent in the fourth embodiment;

FIG. 20 is a front perspective view of the light emitting diode in accordance with the fourth embodiment of my new design;

FIG. 21 is a front view of a light emitting diode in accordance with a fifth embodiment of my new design, the only difference between the fifth and the first embodiment being that the

fifth embodiment includes a cathode mark attached to the rear side of the attachment portion of the light emitting diode;

FIG. 22 is a rear side view of the light emitting diode in accordance with the fifth embodiment of my new design;

FIG. 23 is a top plan view of the light emitting diode in accordance with the fifth embodiment of my new design;

FIG. 24 is a bottom plan view of the light emitting diode in accordance with the fifth embodiment of my new design;

FIG. 25 is a right side view of the light emitting diode in accordance with the fifth embodiment of my new design;

FIG. 26 is a left side view of the light emitting diode in accordance with the fifth embodiment of my new design;

FIG. 27 is a front perspective view of the light emitting diode in accordance with the fifth embodiment of my new design;

FIG. 28 is a rear perspective view of the light emitting diode in accordance with the fifth embodiment of my new design;

FIG. 29 is a front view of a light emitting diode in accordance with a sixth embodiment of my new design, the only difference between the sixth and the fifth embodiment being that the front surface is translucent in the sixth embodiment;

FIG. 30 is a front perspective view of the light emitting diode in accordance with the sixth embodiment of my new design.

The broken line showing of environment (the remaining structure of the light emitting diode) in the Figures is for illustrative purposes only and forms no part of the claimed design.
